(75) Inventor: **Hyoungshin Park**, Seoul (KR)

* cited by examiner

(73) Assignee: **Samsung Electronics Co., Ltd.**,
Gyeonggi-do (KR)

Primary Examiner — Freda S Nunn

(**) Term: **14 Years**

(74) *Attorney, Agent, or Firm* — Harness, Dickey & Pierce,
P.L.C.

(21) Appl. No.: **29/423,271**

CLAIM

(22) Filed: **May 30, 2012**

The ornamental design for a docking station for portable electronic device, as shown and described.

(51) **LOC (9) Cl.** **14-02**
(52) **U.S. Cl.**

DESCRIPTION

(58) **Field of Classification Search**
USPC D14/432-434, 314, 204, 420, 421, 447,

D14/217, 358, 138 R, 140, 142; D13/107,
D13/108, 146; D8/373; 248/346.03, 176.1;

361/679.41, 679.31, 679.32, 679.4,
361/679.43, 679.55, 679.58, 679.33;
320/109, 112-115; 710/15, 303;
455/557; 439/347, 534

FIG. 1 is a front/right-side/top perspective view of a docking station for portable electronic device showing our new design;

See application file for complete search history.

FIG. 2 is a front-side elevational view thereof;

(56) **References Cited**

FIG. 3 is a rear-side elevational view thereof;

U.S. PATENT DOCUMENTS

FIG. 4 is a left-side elevational view thereof;

D516,025 S * 2/2006 Quinn D13/108
D553,123 S * 10/2007 Solland D14/217
D554,108 S * 10/2007 Solland D14/217
D558,209 S * 12/2007 Ikeda et al. D14/434
D578,061 S * 10/2008 Kristensen D13/110

FIG. 5 is a right-side elevational view thereof;

FIG. 6 is a top-side elevational view thereof;

FIG. 7 is a bottom-side elevational view thereof; and,

FIG. 8 is a perspective view of a docking station for portable electronic device showing our new design in combination with an example electronic device; the broken lines shown in FIG. 8 are for the purpose of illustrating structure that is not part of the claim design, but is considered necessary to show the environment in which the design is associated and forms no part of the claimed design.
